BOILER CLEANER

Application filed January 15, 1923, Serial No. 612,766. Renewed January 20, 1931.

This invention relates to boiler cleaners and refers more particularly to boiler cleaners of the type in which jets of steam or the like are directed against the surfaces to be cleaned. One of the objects of the invention is to provide an improved means for rotating the blower unit and operating the valve which controls the supply of steam to the blower unit. Another feature of the invention is the provision of means for preventing the opening and closing of the valve while the unit is being rotated and in general to provide a new and improved boiler cleaner construction and mechanism for operating the same.

In the drawings:

Figure 1 is an end elevational view partly in section through a boiler cleaner embodying my invention;

Figure 2 is a cross-section on the line 2—2 of Figure 1;

Figure 3 is a vertical cross-sectional view showing a modification;

Figure 4 is a section on the line 4—4 of Figure 3.

Figure 5 is a detail sectional view along the line 5—5 of Figure 3.

Describing first in detail the particular embodiment of my invention shown in Figures 1 and 2, A designates a rotatable blower pipe or blower unit having discharge nozzles B through which steam or the like is adapted to be discharged for cleaning the surfaces of the boiler tubes C or other surfaces to be cleaned.

The blower pipe A receives its steam through ports A', these ports communicating through the chamber A² with the stationary steam inlet B'. For closing the communication of ports A' with inlet B' there is provided a valve D adapted to engage a seat D'. The valve D is carried by the valve stem D² and is operated by turning the sheave or hand-wheel E in the following manner: This sheave wheel E is fixedly secured to the shaft F so that when the sheave wheel is revolved the shaft F also revolves. Assuming that the valve D is against its seat D' the wheel E is revolved to the right. This also turns the worm G which is fixed on the shaft F. The

worm G meshes with the worm gear G'. The latter, however, in this position of the parts is prevented from revolving due to the fact that it is held by the dog H which engages a slot H' in the worm gear hub. The continued operation of revolving the wheel E to the right results in the wheel E, shaft F and worm G being moved forward and as the shaft F carries the valve stem D², in opening the valve D from its seat D'. When, however, the shoulder F' on the worm G abuts against the inner face F² of the worm gear housing this prevents further movement longitudinally of the worm and the valve. However, the proportion of parts is such that at this time the dog H has become disengaged from the slot H'. The mechanism for disengaging the dog consists of a lever H² pivoted at H³ and having a projecting end H⁴ extending into a slot E². As the shaft F is fed forward the shoulder of the slot E² will force the projecting end H⁴ of the lever H² forwardly and thus rock the locking dog H to a position where it will clear the slot H'. Further rotation of the handle E to the right will then revolve the worm gear G', the locking dog H being held out during the further rotation of the wheel E. The blower is then reversed by turning the wheel E into the left-hand direction but the shaft F cannot move longitudinally due to the fact that it is held in by the dog H riding on the surface of the hub H⁵. The blower pipe will then be revolved in the left-hand direction until the slot H' comes back into registration with the dog H. When this registration of the dog H and the slot H' again takes place the dog comes in contact with the lug E⁴ which holds the blower pipe from further rotation and immediately the stem F starts to move to the right and continues this movement until the valve D is brought tightly against the seat D'. It will be noticed that this novel arrangement is not only used for rotating the unit and adjusting the valve but that the unit is positively held from rotation both during the opening and closing of the valve. It is of course understood that the valve could just as readily be one that is forced against its seat as one that is drawn against its seat.

The same broad idea of locking the unit from rotating automatically while the valve is being opened and closed from the same operating member is embodied in the construction shown in Figures 3 and 4.

Describing more in detail this modified form, J designates the stationary supply pipe which through the passage J' and port J² connects to the interior of the valve cage. 10 The length of the periods of admission of steam to the interior of the valve cage J⁴ is controlled by a plate J⁸ which can be adjusted for the various installations right at the place of installation by cutting off a portion of the plate to secure the desired opening in the port or slot. The actual admission of steam to the blower unit is, however, controlled by a valve K carried by the 15 rotating shaft K'. On the outer end the shaft K' is provided with screw threads K² upon which there is loosely threaded the sheave wheel L. The latter carries a set of combination thrust and radial ball bearings L' which prevent the sheave from moving in and out. The shaft K' is also provided with four grooves M. Cooperating with these grooves in the manner hereinafter described and mounted in a suitable housing M⁷ carried by a stationary part of the blower structure are locking dogs M' and M² normally pressed toward the grooves by springs M⁸ and M⁴. The dog M' is provided with a groove engaging portion M⁵ and the dog M² is provided with a groove engaging portion M⁶. It will be noted that the groove engaging portions M⁵ and M⁶ are out of alignment so that the groove engaging portion M⁶ will come to the end of its groove in advance of the groove engaging portion M⁵ when the shaft is moved toward the left. For 20 steadyng the dogs M' and M², suitable members M⁹ may be threaded through the housings M⁷ for engagement in grooves M⁹ formed in the dogs. For opening the valve 25 the sheave wheel L is revolved in the right-hand direction. However, in this position the locking dog M² fitting in one of the slots M will prevent the shaft K' from 30 rotating. The sheave L through the screw threads K² will then act as a nut to feed the shaft K' outward which will result in moving the valve K away from its seat K³. This opening movement will continue until 35 the dog M² reaches the incline N where it starts to rise out of the groove and finally rests on the outer surface of the shaft K'. In this position the shaft K' is free to revolve and at the same time the shoulder O on the shaft K' comes into contact with the shoulder O' on the sheave wheel preventing the screw and shaft K' from running any further outward. In effect that locks the sheave L and shaft K' together as the sheave L continues to be rotated in a right-hand direction. After the shaft K' is free to revolve 40

the continued movement in the right-hand direction of the sheave L will rotate the blower pipe Q so as to properly direct the steam from its jets Q' against the surfaces of the boiler tubes R or at the surfaces to be cleaned. Vanes or splines S on the shaft are provided so that a lateral movement can take place between the shaft K', the driver part T and the valve cage J⁴. After revolving the blower pipe through the desired 45 arc of rotation the sheave wheel is then revolved in a left-hand direction. When the wheel is rotated in a left-hand direction the shaft K' is locked from rotation by the engagement of dog M' in one of the slots M. Continued rotation of the sheave wheel L in a left-hand direction will then feed the threaded portion or worm K² of the shaft inward, moving the shaft K' and the valve K until the latter is finally seated against its seat K³. In this last described construction 50 it will be noted that the right-hand movement only of the sheave wheel is utilized for rotating the unit whereas in the construction shown in Figures 1 and 2 the initial right-hand movement opens the valve and the continued right-hand movement of the wheel rotates the unit and it is then rotated back during the initial left-hand rotation of the wheel but that in both cases the unit is locked from rotation while the valve is being opened and closed so that a positive mechanical 55 operation of the valve takes place which cannot be effected by steam pressure or other factors. 60

For the sake of convenience, this invention has been described as being embodied in a boiler cleaner adapted to clean parts of a boiler. It will be apparent, however, that the invention may also be embodied in similar types of cleaning devices, and it is to be therefore understood that the term "boiler" wherever used in the specification or claims is to be construed as meaning a heat transfer apparatus or fluid heater of any character, while the term "boiler cleaner" is to be construed as meaning a cleaner for any such apparatus. 65

It might be noted further that while there is disclosed in this application a construction in which a sequential actuation of the valve and blower element is effected, a construction of this character is described and broadly claimed in a copending application Serial No. 474,483, filed August 11, 1930. 70

What we claim as our invention is:

1. In a soot blower, the combination with a rotatable blower pipe and a valve for controlling the supply of cleaning fluid to said pipe of a common means for rotating said pipe and actuating said valve adapted upon movement in one direction to open said valve and then automatically rotate the pipe and upon movement in a reverse direction to close 75

- the valve and means to prevent rotation of the pipe while the valve is being opened.
2. In a soot blower, the combination with a rotatable blower pipe and a valve for controlling the supply of cleaning fluid to said pipe of a common means for rotating said pipe and actuating said valve adapted upon movement in one direction to open said valve and then automatically rotate the pipe and upon movement in a reverse direction to close the valve and means to prevent rotation of the pipe while the valve is being closed.
3. In a soot blower, the combination with a rotatable blower pipe and a valve for controlling the supply of cleaning fluid to said pipe of a common means for rotating said pipe and actuating said valve adapted upon movement in one direction to open said valve and then automatically rotate the pipe and upon rotation in a reverse direction to close the valve and means to prevent rotation of the pipe while the valve is being opened and closed.
4. In a soot blower, the combination with a rotatable blower pipe, a valve for controlling the supply of cleaning fluid to said pipe and a common means for rotating said pipe and actuating said valve, said means tending to rotate said pipe during the actuation of said valve; of means for holding the pipe from rotation while the valve is being closed.
5. In a soot blower, the combination with a blower unit and a valve for controlling the supply of cleaning fluid to said unit, of an operating member, means controlled by the operating member for moving the valve a predetermined amount, and means also controlled by the operating member for automatically moving the blower unit, said operating member adapted upon reverse movement thereof to restore the blower unit to its original position without moving said valve and then to automatically move the valve to its original position without moving the blower unit.
6. In a soot blower, the combination with a rotatable blower pipe, a valve for controlling the supply of cleaning fluid to said pipe, and a common means for rotating said pipe, and actuating said valve, said means tending to rotate said pipe, during the actuation of said valve, of means for holding the pipe from rotation while the valve is being opened.
7. In a soot blower, the combination with a rotatable blower pipe, a valve for controlling the supply of cleaning fluid to said pipe, and a common means for rotating said pipe and actuating said valve, said means tending to rotate said pipe during the actuation of said valve, of means for holding the pipe from rotation while the valve is being opened and closed.
8. In a soot blower, the combination with a rotatable blower pipe element and a valve element for controlling the supply of cleaning fluid to said pipe, of members for rotating said pipe and actuating said valve, said members being at all times connected and means for holding one of said members stationary while the other of said members is being moved to actuate the corresponding one of said elements.
9. In a soot blower, the combination with a rotatable blower pipe, and a valve for controlling the supply of cleaning fluid to said pipe, of a common means for rotating said pipe and actuating said valve, said common means including a member adapted upon longitudinal movement to actuate said valve and upon a rotary movement to rotate said blower pipe, and means preventing the rotary movement of said member until the longitudinal movement thereof has been completed.
10. In a soot blower, the combination with a rotatable blower pipe and a valve for controlling the supply of fluid to said blower pipe, of means including a worm for rotating said pipe and actuating said valve, said means being adapted upon movement of the worm in a longitudinal direction to actuate said valve, and upon rotary movement of said worm to rotate said blower pipe, and means insuring the completion of the longitudinal movement of said worm before said rotary movement begins.
11. In a soot blower, the combination with a blower pipe and a valve for controlling the supply of fluid to said pipe, of means including a worm for successively moving said valve and blower unit, and means automatically controlled by the movement of said worm for effecting said successive movement of said valve and blower unit.
12. In a soot blower, the combination with a blower pipe and a valve for controlling the supply of fluid to said pipe, of a gear fixed to said blower pipe, a common means to move said valve to a predetermined point and to actuate said gear, and a detent member engaging said gear and preventing actuation thereof until the valve has been moved to said predetermined point.
13. In a soot blower, the combination with a blower pipe and a valve for controlling the supply of fluid to said pipe, of a member fixed to said blower pipe, a common means to move said member and to actuate said valve, a detent member movable transversely of said first mentioned member and operable to compel a successive movement of said valve and said member.
14. In a boiler cleaner, the combination with a blower pipe adapted to discharge steam or the like and a valve for admitting steam or the like to said blower pipe, of a common means for actuating said blower pipe and opening and closing said valve, means distinct from said valve for effecting an unbalanced force upon said valve when in

open position acting in a direction opposite to that taken by the valve in moving to closed position whereby the actuation of said blower pipe is completed before the valve is moved from open position, and means limiting the travel of the blower pipe.

15. In a boiler cleaner, the combination with a blower pipe, and a valve for controlling the passage of cleaning fluid therethrough, of actuating mechanism for successively operating said valve and moving said blower pipe, said mechanism being mounted for two different types of movement, movement of said mechanism conformable to one type effecting an operation of said valve and movement of said mechanism conformable to the other type resulting in movement of said blower pipe, and locking means operable to limit movement of said mechanism to one of said types at a time.

16. In a boiler cleaner, the combination with a blower pipe, and a valve for controlling the passage of cleaning fluid therethrough, of actuating mechanism for successively actuating said valve and moving said blower pipe, said mechanism being mounted for two different types of movement, movement of said mechanism conformable to one type effecting an operation of said valve and movement of said mechanism conformable to the other type resulting in movement of said blower pipe, and locking means operable to prevent movement of said mechanism conformable to one type until movement of said mechanism conformable to the other type has been completed.

17. In a soot blower, the combination with a movable blower pipe and a valve for controlling the supply of cleaning fluid to said pipe, of a common means for opening said valve while said blower pipe is stationary and for then moving said blower pipe, and means independent of said valve for limiting the periods of admission of cleaning fluid to said blower pipe during movement of the latter.

18. In a soot blower, the combination with a movable blower pipe and a valve for controlling the supply of cleaning fluid to said pipe, said valve being movable with said pipe and also relative thereto, of a common means for first moving said valve relative to said pipe to open the valve and for then moving said valve with said blower pipe.

19. In a soot blower, the combination with a rotatable blower pipe, of a valve for controlling the flow of cleaning fluid to said blower pipe, said valve being rotatable with said blower pipe and also movable relative thereto, a stem for said valve, and means associated with said stem for first moving said stem to move said valve to open position and for then moving said stem to rotate said valve and blower pipe as a unit.

20. In a soot blower, the combination with

a movable blower pipe and a valve for controlling the flow of cleaning fluid to said blower pipe, of a member mounted for movement in two directions, means operable upon movement of said member in one direction to first open said valve and then move said blower pipe and operable upon movement of said member in the other direction to then close said valve without movement of said blower pipe and means for holding said blower pipe against movement during opening of said valve.

21. In a soot blower, the combination with a rotatable blower pipe and a valve for controlling the flow of cleaning fluid to said blower pipe, of a stem for said valve, a member rotatably mounted on said valve stem, and means associated with said member and said valve stem operable upon rotation of said member in one direction to first open said valve and to then rotate said blower pipe and operable upon rotation of said member in the other direction to close said valve.

22. In a soot blower, the combination with a rotatable blower pipe and a valve for controlling the flow of cleaning fluid to said blower pipe, of a stem for said valve, said stem being mounted for longitudinal movement without rotation thereof to actuate said valve and being mounted for rotative movement and so connected to said blower pipe as to rotate the latter upon rotation of the stem, and means for successively effecting said longitudinal and rotative movements of said stem.

23. In a soot blower, the combination with a rotatable blower pipe, and a valve for controlling the flow of cleaning fluid to said blower pipe, of a stem for said valve having a threaded portion, said stem being mounted for longitudinal movement to actuate said valve and being mounted for rotative movement to rotate said blower pipe, and means including a sheave wheel threaded on said valve stem for successively effecting said longitudinal and rotative movements of said valve stem.

24. In a soot blower, the combination with a rotatable blower pipe, and a valve for controlling the flow of cleaning fluid to said blower pipe, of a stem for said valve, said stem being provided with a threaded portion and with longitudinally extending grooves adjacent said threaded portion, and means including a sheave wheel threadedly engaging the threaded portion of said valve stem and members engageable in the grooves of said valve stem for first effecting a longitudinal movement of said valve stem to open said valve and for then effecting a rotation of said valve stem to rotate said blower pipe.

25. In a soot blower, the combination with a rotatable blower pipe and a valve for controlling the supply of cleaning fluid to said blower pipe, of means for successively mov-

- ing said valve to open position while said blower pipe is stationary and for then rotating said blower pipe, and means for controlling the periods of supply of cleaning fluid to said blower pipe while said valve is in open position and said blower pipe is being rotated. 5
26. In a soot blower, a movable blower pipe, a two-part valve for controlling the admission of cleaning fluid to said blower pipe, one of said valve parts being fixed on said blower pipe, means for effecting a movement of one of said valve parts relative to the other while the other is stationary to admit 10 cleaning fluid to said blower pipe, and means for moving said valve parts and said blower pipe together as a unit to direct jets of cleaning fluid from the blower pipe toward the parts of the boiler to be cleaned. 15
27. In a soot blower, a rotatable blower pipe, a two-part valve for controlling the admission of cleaning fluid to said blower pipe, one of said valve parts being fixed on said blower pipe, and means for effecting a relative movement between said valve parts while one of said valve parts is stationary to admit 20 cleaning fluid to said blower pipe and for then rotating said valve parts and said blower pipe together as a unit to direct jets of cleaning fluid adjacent portions of the boiler to be cleaned. 25
28. In a soot blower, the combination with a rotatable blower pipe, and a valve for controlling the supply of cleaning fluid to said pipe, said valve being movable with said pipe and also relative thereto, of means for effecting a relative movement between said blower pipe and said valve to open said valve and for then rotating said valve and blower pipe as a unit to direct jets of cleaning fluid adjacent portions of the boiler to be cleaned. 30
29. In a boiler cleaner, a blower movable to direct a jet of cleaning fluid adjacent the portions of the boiler to be cleaned, and a member for controlling the supply of cleaning fluid to said blower and for moving said blower, said member being axially aligned with said blower and being mounted for two types of movement, movement of said member conformable to one type controlling the supply of cleaning fluid to the blower and movement of said member conformable to the other type effecting a movement of said blower. 35
30. In a boiler cleaner, a rotatable blower, and a member for controlling the flow of cleaning fluid to said blower and for rotating said blower, said member being axially aligned with said blower and being mounted for rotative and longitudinal movements, longitudinal movement of said member controlling the flow of cleaning fluid to said blower, and rotative movement of said member effecting a rotation of said blower to direct a jet of cleaning fluid from the same 40
- adjacent the portions of the boiler to be cleaned. 45
31. In a boiler cleaner, a blower element, a valve controlling the flow of cleaning fluid to the said blower element, means for rotating the said blower element and for actuating the said valve, and means separate from said valve actuating means for influencing the actuation of said valve to cause the same to open before rotation of the blower element and to close after rotation of the blower element. 50
32. In a boiler cleaner, the combination with a rotary blower element, a valve seat carried by said element, and a valve cooperating with said valve seat for controlling the passage of cleaning fluid to said blower element, said valve being movable longitudinally of said blower element, of a rotatable driving member, and means for operating said valve during a portion of the rotation of said driving member and for operating said blower element during another portion of rotation. 55
33. In a boiler cleaner, the combination with a rotary blower element, and a valve for controlling the passage of cleaning fluid through said blower element, of a rotatable member connected to said valve, a second rotatable member operatively connected to said blower element, and means upon said rotatable members for moving said first-mentioned rotatable member longitudinally to open and close said valve, and means coacting with said last mentioned means for rotating both rotatable members together. 60
34. In a soot blower, a rotatable blower pipe, a valve seat member, a valve member cooperating with said valve seat member for controlling the flow of cleaning fluid to said blower pipe, a rotatable actuating member, means operable upon rotation of said actuating member in one direction to first effect a relative movement between said valve seat member and said valve member to admit 65 cleaning fluid to said blower element and to then rotate said blower element through a predetermined arc, said means being operable upon rotation of said actuating member in a reverse direction to first move said blower element in a reverse direction through said arc and to then effect a relative movement of said valve seat member and valve member to cut off the supply of cleaning fluid to said blower element, and means operable to positively prevent relative movement between said valve member and said valve seat member incident to a cutting off of the supply of cleaning fluid to the blower pipe during rotation of the blower pipe in both directions through said arc. 70
35. In a soot blower, a blower pipe mounted for oscillation, means for controlling the flow of cleaning fluid to said blower pipe including a valve seat member and a valve 75

member engageable with said valve seat member, a member mounted for oscillation for oscillating said blower pipe, means operable upon oscillation of said member to first effect a relative movement between said valve seat member and said valve member to admit cleaning fluid to said blower pipe, and means operable to positively hold said valve members in position to admit cleaning fluid to said blower pipe during one complete oscillation of said blower pipe.

36. In a boiler cleaner, the combination with a blower unit movable about its axis, of a valve casing with which said unit communicates, said casing having an inlet for a cleaning fluid, a valve in said casing controlling the fluid supply to said blower pipe, and a common actuating member for said blower pipe and valve member slidably connected in said casing to the blower pipe.

37. The combination with a rotatable blower element, of a valve movable relative to said blower element for controlling the admission of cleaning fluid thereto, said valve being rotatable in unison with said blower element, and means operable in timed relation to the rotation of said blower element for securing the relative movement of said valve and blower element, said means being arranged to permit an angular movement of said blower element through an angle equal at least, to 360 degrees.

38. In a boiler cleaning apparatus, the combination with a movable blower element having an enlarged chamber on one end and a port in the said chamber eccentric to the axis of the element, of a cleaning fluid supply conduit for the said element, a head assembly forming a connection between said conduit and said blower element, a valve for controlling the flow of cleaning fluid through said head assembly, and means for moving said blower element and for actuating said valve.

45. In testimony whereof we affix our signatures.
